COMBINED COMPACT AND LIPSTICK HOLDER

Allan B. Goldenthal, New York, N. Y.

Application September 1, 1954, Serial No. 32,102

Term of patent 14 years

(Cl. D86—10)

FIG. 1.

FIG. 2.

Fig. 1 is a top plan view of a combined compact and lipstick holder, showing my new design; and

Fig. 2 is a side view thereof.

The side opposite that shown in Fig. 1 is substantially plain.

I claim:

The ornamental design for a combined compact and lipstick holder, as shown and described.
